UNITED STATES PATENT OFFICE.

PETER K. DEDERICK, OF LOUDONVILLE, NEW YORK.

BALE-BAND MACHINE.

SPECIFICATION forming part of Letters Patent No. 586,831, dated July 13, 1897.

Application filed August 24, 1893. Serial No. 483,945. (No model.)

To all whom it may concern:

Be it known that I, PETER K. DEDERICK, of Loudonville, in the county of Albany and State of New York, have invented certain new and useful Improvements in the Manufacture of Bale-Bands; and I do hereby declare the following to be a full, clear, and exact description of the same, reference being had to the accompanying drawings, forming a part of this specification, and to the letters of reference marked thereon.

This invention has for its object to simplify the manufacture or formation of wire bale-bands such as have an eye or twisted portion at one or both ends to facilitate the tying of the bales.

Referring to the accompanying drawings, Figure 1 is a front elevation of the preferred form of machine. Fig. 2 is a top plan view of the same. Fig. 3 is an enlarged perspective view of one of the twisting-heads. Fig. 4 is a perspective view of a slightly-modified form of machine.

Similar letters of reference in the several figures indicate the same parts.

In many of the machines for making bale-ties heretofore employed the ties have been made one at a time. With my invention I propose to make a number of ties at once, thus greatly simplifying their manufacture. With this idea in view, then, I provide a frame (lettered A in the drawings) made somewhat in the form of a table or bench, and upon it, preferably near one end, mount a series of twister-heads G, all geared together so as to rotate in unison. For gearing these heads together I preferably provide each with a small toothed pinion b, meshing with the pinions on the next adjacent heads, and upon one of the twister-head shafts mount a mechanism for imparting rotation to the whole series. This may consist of a simple crank-handle or preferably, as shown, a beveled gear b', meshing with a corresponding beveled gear mounted on a crank-shaft extending out on the front side of the machine.

In front of the series of twister-heads G a clamping-plate C is mounted and adapted to hold the strands of wire against twisting, this device being of any preferred form, and inasmuch as it is well known in the art it needs no further description.

In proximity to the machine-bed A, and preferably upon a rearward extension D of the same, I mount a series of reels E, upon which bobbins or coils of wire from which the bands are to be made are mounted. When the reels are mounted in rear of the bed, in order to guide the strands back to the twister-head I preferably provide a large drum or guide-wheel F at the end of the bed and rearward extension D. This enables the wires to be turned around to the front of the machine in position to be readily grasped by the operator and carried forward to the twister-heads. At the same time the reels are in position to be readily inspected and repaired without the necessity of the operator leaving his post in front of the machine.

In line with the twister-heads and at the opposite end of the bed is a guide for the several strands of wire, consisting, as shown in Figs. 1 and 2, of a pair of bottom rolls f and an intermediate top roller f', and the wire is preferably manipulated between these guide-rollers, which hold the strands in their relative normal position, and the opposite twister-head. Thus there is little danger of the wires getting out of shape.

In some instances it is desirable to form bale-ties having an eye or twisted portion at each end, and if this be the case a second twister-head B is mounted on the bed in proximity to the guides f. This twister-head has a series of twisters corresponding to those before described and operating in a similar manner.

Should it be desired to stretch the bale-bands after their formation, it is accomplished by having one of the heads movable by means of a toggle H and foot-lever H' or rack and pinion or other well-known equivalent, and after the twisting operation is completed the head may be moved to strain and straighten the bands.

In addition to making one of the heads movable, one of the heads G is also made preferably adjustable, in order to provide for making bands of different dimensions, said head being provided with slots g', through which pass bolts g² or other suitable securing device to accomplish this adjustment.

In proximity to the twister-head B a knife or cutter I is provided for severing the strands

into proper lengths, preferably after the twist has been made at the farther end.

- Obviously a series of wire-reels need not be located in rear of the bed-frame, but may be located at one end or any other convenient position. As shown in Fig. 4, for instance, a cross-piece K is mounted at one end of the bed, and the wire-reels are adjustably mounted upon it. In this figure also I have combined the guiding and stretching mechanism by providing a pair of pivoted cam-gripping jaws, which may be made to first grasp the wire and then swing back to stretch those upon which the loops have been formed.
- 15 This combined guiding and stretching device consists, essentially, of a pivoted lever M, having a gripping-jaw *m* near the lower end, and a second pivoted member N, having a cam-shaped gripping-jaw *n* at the lower end.
- 10 o adapted to clamp the wires against the jaw *m*. In other respects this form of machine is similar to that just described and needs no further explanation.

In operation, assuming that the machine has been threaded up, so to speak—that is to say, the wires drawn from the reels and the whole series passed through and arranged in relative position in the guides—the operator, who is provided with a pair of long-nosed pincers P, grasps the ends of the whole series of strands, gives the same a half-turn, so as to form a series of long hooks. Then walking to the other end of the machine he draws the whole series of strands and loops each one separately over one of the twister-heads, arranging the body of each strand and its reversed end in the slotted retainer C, so as to prevent them from twisting. Then by turning the crank-handle the whole series of strands are twisted at one operation and the loops formed thereon. Leaving these loops on the twister-heads, the operator now walks to the other end of the machine and severs the strands in front of the guide, and if the bands are simply to have one loop or twisted end they are ready for removal; but assuming that they are to have both ends looped or twisted the operator places each strand on its twister-head at that end of the machine, as

before described, and forms the loop or twist thereon. Then if the bands are to be stretched the head is moved back by the toggle and foot lever or other means before mentioned, and then the bands are released at this end of the machine and the operator, grasping the ends of the wire projecting through the guides, proceeds to double them back, as shown in Fig. 4, and draw them through the guides to the opposite end of the machine. Then throwing off the bands previously formed from the twister-heads at this end of the machine he loops the new ends on and proceeds as before described.

In operating the structure shown in Fig. 4 when the loop has been formed at the farther end the combined guide and stretcher is clamped tightly by grasping its upper end and swinging it back, thus stretching the wire, and then the strands are severed in front of it. This form of machine is especially adapted for use where the bands are to have but one end looped or twisted, but is capable of use with the other form of machine, as will be readily understood.

Having thus described my invention, what I claim as new is—

1. In a bale-band-forming machine, the combination with the frame and the series of twister-heads geared together and mounted on a base adjustable on the frame, of a series of wire-reels mounted on the frame, individual guides for each of the strands of wire, a wire-clamp cooperating with all the wires and a stretching mechanism for straining the twisted bands; substantially as described. 85

2. In a bale-band-forming machine, the combination with the base, the series of twister-heads geared together for simultaneous rotation and mounted on the base, of the series of wire-reels mounted in rear of the base, and the drum or wheel at the end around which the wires are turned; substantially as described. 90
